UNITED STATES PATENT OFFICE.

LIVIN STAS, OF TACOMA, WASHINGTON.

CAR-STAKE.

No. 858,834.

Specification of Letters Patent.

Patented July 2, 1907.

Application filed January 29, 1907. Serial No. 354,729.

To all whom it may concern:

Be it known that I, LIVIN STAS, a citizen of the United States of America, residing at Tacoma, in the county of Pierce and State of Washington, have invented certain new and useful Improvements in Car-Stakes, of which the following is a specification, reference being had therein to the accompanying drawing.

This invention relates to car stakes and especially for cars for use in the lumber trade for shipping logs and sawed timber and has for its objects to provide a stake of solid construction permanently fixed to the car and which shall be able to stand the hard usage incident to shipping logs; to provide means whereby the stakes on each side are all held upright; to provide means for removing said holding device from the opposite side of the car, so that all the stakes on one side may be removed without endangering the life of the employee operating them; to provide locking means whereby accidental releasing of stakes is prevented; to provide 20 adjustable posts adapted to fit in the car stakes to hold a load of sawed timber; and to provide an adjustable tie bar, joining the tops of each pair of posts.

I attain these objects by the mechanisms and devices illustrated in the accompanying drawings, in which 25 Figure 1 is a vertical section of the deck of a flat car, showing my car stakes and posts mounted thereon; Fig. 2 is a side view of the top of one of the posts, showing a portion of the tie bar; Fig. 3 is an end view thereof; Fig. 4 is a vertical section of the adjustable clamp 30 in the tie bar; Fig. 5 is a front view of the car stake; Fig. 6 is a side view thereof, the bracket being in section to show the stake; Fig. 7 is a similar view, showing a stake without the operating lever; Fig. 8 is a view similar to Fig. 6, showing the stake released and turned 35 down; Figs. 9 and 10 are front and side views, respectively, of the stake operating and locking mechanism, in the locked position; and Figs. 11 and 12 are similar views, showing the mechanism in its unlocked position.

Similar numerals of reference refer to similar parts 40 throughout the several views.

To each of the side sills 1 of a flat car are secured two, or three, or four brackets 2 which support the car stakes. These brackets 2 consist of a back plate and two side ears 3 open on the top, the bottom, and the outer side, 45 except for a short lug or stop 4 on the inner end of the top, against which the car stake rests when in its vertical position. A bolt or pin 5 passes through the ears 3 near the lower outer edge thereof as shown in the drawings. This pin 5 is made very strong and supports the 50 car stake 6 for which it acts as a pivot.

The car stake 6 is made hollow and has its upper end beveled off at about an angle of 45 degrees as shown. The shape of the stake 6 is such that, when it is in its vertical position, the main part above the car deck is 55 vertical and is inside of pivot 5 and rests against the edge of the stop 4, the part reaching from the straight

upper body to the pivot being preferably curved as shown. A depending extension 7 is also formed integral with the car stake below the pivot 5 said extension being provided with a notch 8, in its inner lower 60 edge, adapted to engage the roller of the stake holder. A pair of small side lugs 9 are also formed on the sides of the stake 6 to brace it from side motion against the ears 3 as shown in Fig. 5.

The stakes are all held in their vertical positions by 65 the rollers 10 which engage the notches 8 of the extensions 7 to prevent the rotation of the stake on the pivot 5. The rollers 10 are mounted on arms 11 secured to the shaft 12 which extends through all the brackets on one side of the car. The position of the shaft 12 is such 70 as to bring the arms 11 in horizontal position when engaging the extension 7, so that the strain thereon will not tend to force the arms downward and the rollers out from the engaging position. For this reason the lower part of the notch 8, above mentioned, is made on a 75 curved line, having the center of the shaft 12 for its center, so that any motion of the arms 11 does not affect the stake 6 until the roller has passed out of said notch.

In practice I mount the arms 11, as shown in Fig. 7, on 80 all the brackets except one on each side, and in that one I mount the arms 13 (Fig. 6). These arms 13 are similar to the arms 11 but have an operating lever 14 formed thereon, and depending downward therefrom as shown, said operating lever 14 being connected to the other side of the car by the operating rod 15 in which a turn-buckle 16 is mounted for adjusting purposes. Thus when all the stakes on one side of the car are to be released the rod 15 is pulled, which turns the shaft 12 and the arms 11 and 13 and moves all the rollers 10 downward out of the notches 8 in the extensions 7, thus freeing 90 all the stakes 6 and allowing the pressure of the logs, or other load, to push the stakes outward on their pivots so that they drop into the positions shown in Fig. 8.

In order to control the rods 15 from the other side of the car and in order to prevent their being accidentally 95 moved I have devised the following supporting and locking mechanism, which is secured preferably to the inner sides of the outer side sills 1. The rod 15 is secured to the end of the arm 17 which is mounted on the pivot, or shaft, 18 which passes through the hub 19 of 100 the arm 17. This hub 19 has a portion of its upper surface cut away to leave the two cross lugs 20 extending upward therefrom. The shaft 18 is mounted in the brackets 21 of the casting 22. A latch 23 is pivoted to the casting 22 at right angles to the shaft 18 and has its 105 lower portion adapted to engage between the lugs 20 on the hub 19. It is also provided with a weighted handle 24 extending at an angle, so that its weight will tend to keep the end of the latch 23 between the lugs 20 and against one of the brackets 21 of the casting 22. This 110 latch 23 is further locked, in its locking position, by the arm 25 of the second latch, said arm being pivoted also

to the casting 22 and resting on a lug formed on the casting and being directly in line with the end of said latch 23 so as to prevent its turning on its pivot to pass from between the lugs 20. This arm 25 is also provided with 5 a short handle 26. Thus when it is desired to release the car stakes 6 on one side of the car, the locking apparatus, on the other side, is unlocked by turning the latches 25 and 23, into the positions shown in Fig. 11, and then turning the shaft 18 and the arm 17 which pulls 10 the rod 15 and releases the car stakes as already described.

When the car is to be used for shipping small poles, cord wood or sawed lumber the stakes 6 are raised into their working position and the iron posts 27 are inserted 15 therein. The posts 27 are tubular and are about five feet long. Inside of the post 27 is a smaller tube 28 of about the same length. The tube 28 is provided with a collar 39 near its top to prevent its falling all the way into the tube 27 when it is not in use. The tubes 28 are 20 then fastened together by the adjustable tie bars which rest on the top of the load, the tube 28 being slid down inside of the tube 27 to bring the tie bar to the proper height. The top of each tube 28 has a vertical notch 29 across it into which the end of the tie bar fits. A hole 25 30 is made in the tube 28 below the notch 29 into which the hooked end 31 of the tie bar fits, as shown in Figs. 2 and 3. The tie bar consists of two flat bars 32 and 33 each provided with the hooked ends engaging in the notches 29 and the holes 30 in the tubes 28. To the bar 30 32 is secured a sleeve 34 into which the bar 33 passes. The bar 33 has a series of teeth 35 formed on its upper surface near its end, into which the latch 36 mounted in the sleeve 34 engages to hold the bars together. The latch 36 is secured to the pivoted handle 37 and is kept 35 pressed into the teeth 35 by means of the spring 38.

When it is desired to unload, or to take down the posts for any reason, the handle 37 is depressed thus raising the latch 36 from the teeth 35 and releasing all connection between the bars 32 and 33 which may then be unhooked from their respective tubes 28; then the tubes 27 are pushed down into the tubes 28; then the tubes 27 are removed from the stakes 6; then the stake latches are unlocked and the stakes released as already described, and the tubes 27 with the tubes 28 inside them 40 are stowed away in a receptacle provided therefor.

Having described my invention, what I claim is:

1. In a car stake, the combination of an open bracket, a vertical stake pivoted thereto and adapted to move outward from the car, a depending extension formed on said stake, a stop engaging said extension to prevent the stake turning outward on its pivot and being secured to a horizontal shaft, a lever secured to said shaft to turn it and 50

remove said stop from engagement with said stake extension, and a bar extending across the car under the deck thereof and secured to said lever to control and operate it. 55

2. In a car stake, the combination of an open bracket, a vertical stake pivoted thereto and adapted to move outward from the car, a depending extension formed on said stake, a stop engaging said extension to prevent the stake turning outward on its pivot and being secured to a horizontal shaft, a lever secured to said shaft to turn it and 60 remove said stop from engagement with said stake extension, a bar extending across the car under the deck thereof and secured to said lever to control and operate it, and supporting and locking means mounted on the other side 65 of the car whereby said bar is held from moving.

3. In a car stake, the combination of a pivoted car stake, a pivoted stop controlling said stake, a lever connected to said stop to move it from said car stake, a bar secured to said lever and passing to the other side of the car, a pivoted lever mounted on the other side of the car and secured to the other end of said bar, a lug formed on said lever to prevent it from turning on its pivot, and a pivoted latch engaging said lug and removable therefrom. 70

4. In a car stake, the combination of a pivoted car stake, 75 a pivoted stop controlling said stake, a lever connected to said stop to move it from said car stake, a bar secured to said lever and passing to the other side of the car, and a pivoted latch adapted to prevent the movement of said bar when said latch is in engagement therewith.

5. In a car stake, the combination of a pivoted car stake, a pivoted stop controlling said stake, a lever connected to said stop to move it from said car stake, a bar secured to said lever and passing to the other side of the car, a pivoted lever mounted on the other side of the car and secured 85 to the other end of said bar, a lug formed on said lever to prevent it from turning on its pivot, a pivoted latch engaging said lug and removable in one direction therefrom, and a second latch engaging said first latch to prevent its movement and removable therefrom. 90

6. In a car stake, the combination of a pair of vertically hollow stakes one on each side of the car, hollow telescopically adjustable posts extending upward from each of said stakes, longitudinal bars extending inward from and removably secured to the upper ends of each of said posts, 95 and a clamp secured to one of said bars and adjustably engaging the other bar to tie the said bars and their posts together.

7. In a car stake, the combination of a pair of vertically hollow stakes one on each side of the car, hollow telescopically adjustable posts extending upward from each of said stakes, longitudinal bars extending inward from and removably secured to the upper ends of each of said posts, a series of teeth formed on one edge of one of said bars, a clamp piece secured to the other bar and inclosing the 100 end of said first bar and the teeth thereon, and a spring actuated removable dog mounted in said clamp piece and engaging said teeth to tie the bars together. 105

In testimony whereof I affix my signature in presence of two witnesses.

LIVIN STAS.
